UNITED STATES PATENT OFFICE.

WILLIAM MCPHERSON, OF NEW YORK, N. Y.

DOVETAILING-MACHINE.

SPECIFICATION forming part of Letters Patent No. 518,824, dated April 24, 1894.

Application filed December 5, 1892. Serial No. 454,078. (No model.)

To all whom it may concern:

Be it known that I, WILLIAM MCPHERSON, a citizen of the United States, residing in the city and county of New York, in the State of New York, have invented a certain new and useful Improvement in Dovetailing-Machines, of which the following is a specification.

The invention makes the blind dove-tail recesses which receive the dove-tail ends of another board. It makes the recesses matching exactly to the dove-tails cut in the ordinary form on the other piece.

The improved machine may be made of any size, but the invention is intended more particularly for small machines operated by manual power. I will describe it as so operated.

The machine employs a pair of chisels carried in properly inclined guides, and having the cutting edges ground at a corresponding angle. These chisels are brought down simultaneously and cut their corresponding parts not of the same recess but of two adjacent recesses, one chisel cutting the inclined side of the first, inclining to the right, and the other similarly cutting the inclined side of the second, inclining to the left, numbering the recesses from right to left. The board to be treated is previously nicely squared and clamped upon the uppermost part of a duplex carriage, and the feeding is effected by moving these carriages. There are two motions, one a slight motion of both carriages, step-by-step, forward,—this determines how thick a shaving shall be taken by the chisels at each descent. The gradual moving of the board forward toward the operator by such feed goes on until the cut which began on the extreme end of the board has extended the recesses inward to the required depth. I provide mechanism for stopping the operation at the right point, and returning the carriage, causing it to retreat until its end is again a little within the line of the chisels. The motions so far as yet described have been performed by both the upper and lower carriages. At this juncture I move another, a third chisel, which is guided in horizontal ways, and by its aid smooth the bottom of the recess which is likely to be left a little ridged by the successive cuts. Next, the board with the upper carriage alone is moved to the right

to an extent just equal to the distance between one recess and the next, and now the treadle being again operated another succession of cuts are made by the chisel, and the board is again fed forward by small increments, and these operations are successively repeated until the dove-tail recesses are produced quite across the end of the board. I provide for adjusting the interval between each dove-tail recess and the next so as to make them come out even with all widths of wood.

The accompanying drawings form a part of this specification and represent what I consider the best means of carrying out the invention.

Figure 1 is a front view of the principal part of the machine with the extreme front removed. A section of the horizontal chisel at the front appears near the center of this figure. A piece of wood is shown in place in the act of being treated. Fig. 2 is a corresponding side elevation. Fig. 3 is a side elevation of the extreme front portion showing the adjacent parts in vertical section. Fig. 4 is a corresponding plan view and horizontal section.

Similar letters of reference indicate corresponding parts in all the figures where they appear.

A is a fixed framework of cast iron or other suitable material. Horizontal ways, A', A', A², A², shown in dotted lines in Fig. 1, support and guide a carriage B which is capable only of moving right and left. A rack B' in its under face is engaged by a pinion C' on the feed-shaft C, which is mounted in fixed bearings, and is turned by small increments, as will presently appear.

A³, A⁴, are inclined uprights fixed at adjusted distances apart, in which sliding blocks D, D, are guided, carrying chisels D', D'. These chisels are not only beveled like ordinary chisels, as shown in Fig. 2, but also have their edges each sufficiently out of the right angle with the line of the length to compensate for the obliquity of their position so that their cutting edges are always level, as shown in dotted lines in Fig. 1. The arrangement is such that each chisel in its descent makes an inclined cut, adapted to produce one side of a dove-tail cavity m, and the other chisel,

correspondingly inclined in the opposite direction, in its simultaneous descent cuts the opposite side not of the same but of another similar dove-tail recess. I will designate each 5 entire dove-tail cavity by the letter m , and the two parts of which it is constituted, and which are excavated at different times, by adding super-numerals, as m' , m^2 .

The movements of both the blocks D, D, 10 and their respective chisels are effected at a single depression of a treadle, not represented, which is connected by rods E to pins set in the blocks D. Slots a are provided in the inclined guides A', A², which allow the pins 15 to play, as will be readily understood.

B² is the upper carriage, mounted on the main carriage B, and capable of a motion transversely to the motion thereof. It is equipped with clamps B³ which are adjustable 20 on the carriage B², and equipped with clamping screws B⁴ adapted to serve in the obvious manner, clamping the board M which is to be treated.

The feeding of the carriages forward is effected at each ascent of the chisels and their attachments by means of a lever G turning on a fixed center set on an arm on the upright A⁴. One end carries an adjusting screw G' which is struck at each ascent of the chisels by a collar D³ set on the corresponding block D so as to turn the lever G a little, and the motion thus imparted is communicated through a rod H to a lever I turning loosely on the over-hung end of the shaft C. The 30 other end of this lever carries a pawl J actuated by a spring J' which urges it into engagement with the teeth of a ratchet-wheel C² which is keyed or otherwise firmly set on the shaft C. At each descent of the chisels the 35 lever I is turned by a spring, G², in the direction to slip the pawl over one or more teeth of the ratchet; and at each ascent of the chisels the lever G is rocked by its receiving a slight blow through the screw G' which 40 presses the rod H and turns the lever I, pulling the pawl J again into its highest position and correspondingly turning the shaft C and through the pinion C' feeding the carriages B, B², with the board M forward. This work 45 proceeds at each descent of the treadle until the board M has been carried forward so far that the dove-tail recesses m' , m^2 , have been excavated to the required depths by the successive strokes of the chisels D', D².

50 It will be observed that the recesses m^2 excavated by the chisel D² is not a part of the same dove-tail cavity to which the recess m' excavated by the chisel D' belongs. It is one dove-tail space in advance. The chisel D² cuts an independent channel in the wood, ready when the other chisel D' acts to form its part of a proper dove-tail recess. The width of the chisels should be such that the action of the two completes or nearly completes the proper dove-tail recess. The presence of a very slight ridge at the bottom is of no consequence, but such ridge should be

something smaller than is shown in the drawings.

The bottom of the dove-tail recess is finished smoothly by a separate chisel P of the proper width and having the sides beveled which is mounted in horizontal ways A⁵, and is operated by a lever Q which may be actuated by the hand of the attendant to finish 70 the bottom of each recess m . It traverses at such a level as to remove the roughness left by the descent of the successive chisels, and also the slight ridge, if any, which has been left in the mid-width between the two series 75 of cuts.

When the operator has by the successive descents of the chisels D', D², cut the wood for parts of two dove-tail recesses to the exactly proper depth, the feeding is automatically arrested and the carriages B, B², with the wood M are promptly returned by the force of a weight or spring, U. Mechanism for effecting the stoppage of the forward feeding movement and liberating the carriages to allow 80 them to move backward, is shown in Fig. 2.

The ratchet-wheel C² has a breadth much in excess of the breadth of the hook-pawl J, and receives also another hook-pawl K, which latter instead of being like the pawl J hung 85 on a movable center is hung on a fixed center, a pin set in the fixed framing A. It is actuated by a spring K', urging it equally with its associate pawl into engagement with the ratchet-wheel C². Its function is simply 90 to hold the wheel C² after it has been partially turned by each movement of the pawl K. Each pawl J and K has a rounded head J², K², adapted to receive the action of the hammer L and be moved in opposition to the 95 force of their respective springs J', K' when the period arrives for liberating the carriages and allowing the return motion.

The hammer L turns on a fixed pivot A⁶, and is subject to the force of a volute spring 100 L', tending to throw to the left the head L², which head is of sufficient width to strike the heads J² and K² of both the pawls. Below the axis of the hammer extends a V-shaped arm L³ presented, as shown, to a V-shaped ridge 105 O' on the spring O. On the side of the carriage B adjacent to the hammer are two adjustable stops B⁵ and B⁶. As the carriage moves backward after the chisels have performed their duties and excavated each its 110 respective recess m' , m^2 , the stop B⁵ strikes the head L² of the hammer and moves it into the position shown. When the movement of the carriage B and its attachments forward and the excavation of the recesses m' , m^2 , have 115 proceeded to the proper extent, the stop B⁶ pushes the head L² of the hammer so far forward that the angle of the arm L³ passes the angle of the ridge O'. When this condition is attained the hammer moves smartly forward with the force due to the direct tension of the volute spring L' and also to the wedge-like action of the ridge O'. The hammer 120 moves forward and strikes the heads J² and

K² of the respective pawls J and K with sufficient force to disengage their hook ends from the teeth of the wheel C² and hold them out of engagement. Both pawls are thus held out 5 of engagement while the carriage B and its load runs back, when the stop B⁵ again performs its work of turning the hammer back to the position shown, and the pawls J and K actuated by their respective springs J' and 10 K' again engage with the ratchet-wheel C² and the work is ready after it has been shifted laterally to be again slowly fed forward in the production of the next dove-tail recess.

The shifting of the board laterally to gage 15 the distance between each dove-tail and the next is effected by sliding the upper carriage B² laterally, guided by the tongues B⁸. The movement is effected by a bar R carrying a pawl S which engages with a series of teeth 20 B⁷ on the front edge of the carriage B². The pawl is urged into engagement by a spring S'. The bar is moved at the required periods by a handle R'. Its motion is limited by stops R² R³. After each backward movement of the carriages with the wood M is completed and the horizontal chisel P has 25 done its work, the attendant moves the bar R to the right as far as it will go, thereby effecting a corresponding movement of the carriage B² and the wood M to just the proper 30 extent for the next operation.

I provide for varying the width of the spaces between the several dove-tail recesses when completed. The inclined uprights A³, 35 A⁴, are rigidly held in position during the working of the machine as if they were parts of the fixed framework, but they are capable of adjustment toward and from each other. Each is capable of sliding on its support on 40 the fixed framing A, and carries a nut which is right or left respectively, and receives an endless right and left screw T which is mounted in fixed bearings in the framing A, and may be turned by a wrench applied to the 45 squared end in the obvious manner. F are holding-down bolts which extend up through slots, and F' are nuts fitted thereon by turning down which the uprights are held very stiffly after they have been adjusted in position by the screws. Adjusting the slides apart 50 makes the dove-tail recesses m' m² nearer together, and correspondingly reduces the width of the wood left between the several recesses when completed. To make such adjustment 55 the nuts on the holding bolts F are relaxed, the screw T turned in the proper direction, causing the uprights to move apart to the required extent, then the nuts F' being again tightly set the uprights are again stiffly held 60 in their new positions.

My machine gives a uniform inclination to the sides of the cavities corresponding to the inclination of the guide-ways in the uprights. The width of the chisels D', D², may be varied, and their position may be varied within 65 limits by obvious means so as to somewhat vary the width of the dove-tail recess. The

distance of the dove-tail recesses apart may be varied with great nicety by the well known expedient of providing a number of pawls of different lengths engaging in the teeth at different stages of the movement so as to give the effect of finer teeth, and allow any degree of fineness in the variation of the extent of traverse. Such pawls may all be mounted on 70 the same pin and worked by one movement of the handle. I believe that one, as shown, will suffice for all ordinary uses.

Various other changes may be made without departing from the principle or sacrificing the advantages of the invention. I can vary the arrangement of the springs for actuating the hammer L. The spring L' may be dispensed with and the spring O with its V-shaped ridge O' depended upon to give a 85 sufficiently smart forward movement to the hammer at the period when it is required to be effective.

I attach importance to the fact that my chisels are arranged to cut each a part of a 90 separate and distinct recess, because it allows the two chisels to be brought into action simultaneously, each in its respective recess, thus effecting a great saving of time over what would be required if one chisel had to 95 descend and return before the other could descend.

I attach importance to the provisions for automatically liberating the carriage and allowing it to return after each cut, by accumulating power in the spring O, before the feeding is concluded, and using it through the intervention of the hammer L to forcibly and reliably move the pawls J K into their idle positions; and to the fact that in the returning movement the step B⁵, by the act of turning the pawls J K into the position for engagement, returns the hammer L again into its oppositely inclined position, and all the parts are again reliably set for effective feeding. This mechanism avoids all chance of leaving the parts in an intermediate position.

I claim as my invention—

1. In a dove-tailing machine, two inclined chisels carried in inclined ways, set at such 115 distance apart that they will each cut respectively parts of two separate and distinct dove-tail recesses, in combination with mechanism adapted for bringing down both chisels simultaneously and with mechanism to feed 120 the wood forward a proper amount at each cut and with mechanism to change the position of the table carrying the wood after each recess is completed, substantially as herein specified.

2. In a dove-tailing machine, two inclined chisels carried in inclined ways, adapted to cut respectively parts of two dove-tail recesses, and mechanism adapted to feed the wood forward a proper amount at each cut, 130 in combination with stops B⁵ B⁶ on the carriage and with pawls J K and means for operating them from the treadles, the pivoted hammer L and the spring O, substantially as

specified for automatically liberating and allowing the carriage to be returned after each movement, substantially as herein specified.

3. In a dove-tailing machine, two inclined chisels carried in inclined ways, set at a proper distance apart to cut respectively parts of two separate dove-tail recesses, and mechanism adapted to feed the wood forward a proper amount at each cut, in combination with the horizontal chisel and the lever Q adapted to be operated after the dove-tail recess is otherwise completed, and to remove at

a single operation a small quantity from the bottom of each dove-tail recess, all arranged for joint operation substantially as herein specified.

In testimony that I claim the invention above set forth I affix my signature in presence of two witnesses.

WILLIAM MCPHERSON.
